DEEP WELL TOOL

Idris Thomas, Whittier, Calif.

Application May 3, 1937, Serial No. 140,461

6 Claims. (Cl. 294—94)

This invention relates to deep well tools. The invention may be embodied in spears and sockets, or other tools for making a connection to tubing or casing within a well for backing-off operations, or other operations. As ordinarily constructed, tools of this type include movable slips which are set against the tubing by pulling up on the tool string, and then while the tool string and "fish" are subjected to an up strain, the tool string is rotated to back off the "fish." This operation has the objection that on account of the severe strain or stress to which the "fish" is subjected, very high frictional resistance is developed at the threads where the "fish" happens to unscrew.

In another type of fishing tool of this kind that has been in use, the mandrel or the socket is formed with circumferentially spaced cam faces, and after the slips have been set by a slight up pull, the slips are caused to grip the "fish" by a rotation of the tool string on its axis. This latter type of tool gives considerable satisfaction, but in rotating the tool string in the reverse direction to release the slips, if the slips do not release readily there is a tendency for the torque in the tool string to start the left-hand threads to unscrew at some one of the tool joints in the tool string. This would make it difficult or impossible to release the slips.

One of the objects of the present invention is to provide a fishing tool for backing off tubing or casing, which will overcome the objections referred to above, and in which it is unnecessary to subject the tool string to a severe up strain while backing off the tubing or casing; also, to construct the tool in such a way that when there is substantially little or no up strain on the tool string, the slips can be readily released by a rotation in the same direction that gripped the slips on the tool, and which will require the development of only a relatively low torque in the tool string. In other words, the release of the tool would be attained by a rotation not in a direction to unscrew any of the joints of the tool string.

In connection with deep wells, it is sometimes necessary to determine with definite accuracy the depth or level of a cementing point that has occurred previously at some level below the surface. In order to determine cement level in a well, it has been the practice to employ a tool of the type of a spear provided with slips. By gripping the slips in the casing at different levels, and vibrating the tool string or the casing at the well head, it is possible to ascertain the cement

level, by reason of the fact that when the tool is gripped in the casing at the cement, the cement will deaden or reduce the vibrations transmitted back to the well head. One of the objects of my invention is to provide a well testing tool particularly adapted for such use in determining the level of a cemented point in a well.

Further objects of the invention will appear hereinafter.

The invention consists in the novel parts and combinations of parts to be described hereinafter, all of which contribute to produce an efficient deep well tool.

A preferred embodiment of the invention is described in the following specification, while the broad scope of the invention is pointed out in the appended claims.

In the drawings:

Fig. 1 is a side elevation and partial section of a fishing tool of spear type, embodying my invention. This view shows a portion of the tubing or "fish" and illustrates the parts with the slips set against the "fish" preparatory to backing it off. This view also shows the lower end of the drill string broken away.

Fig. 2 is a view very similar to Fig. 1, but showing the slips in their released position, and further illustrating the means employed for releasing the slips. This view shows the parts in the relation they have when the slips have been "cammed" up on the mandrel to release them preparatory to withdrawing the tool.

Fig. 2a is a cross-section on the line 2a—2a of Fig. 2.

Fig. 3 is a horizontal section taken through the spear and the "fish" on the line 3—3 of Fig. 1, but upon an enlarged scale. This view shows the tool after the rotation that causes slips to grip the casing.

Fig. 4 is also a cross-section on the line 3—3 of Fig. 1, but showing the tool after the slips have been set against the casing by a slight up pull of the tool string.

Fig. 5 is a cross-section on the line 5—5 of Fig. 2, showing the relation of the parts after the slips have been "cammed" up to release them from the casing, to permit the tool to be withdrawn.

Fig. 6 is a cross-section taken about on the line 6—6 of Fig. 2, and particularly illustrating stop means which I employ at the lower end of the cage for limiting the rotation of the mandrel with respect to the cage or slip carrier.

Fig. 7 is a side elevation and partial section of a fishing tool embodying my invention, but of

the socket type. This view shows a portion of tubing in the tool, and broken away, and illustrates the slips in their gripping position against the "fish."

5 Fig. 8 is a horizontal section taken about on the line 8—8 of Fig. 7.

Fig. 9 is a vertical section and partial section through a tool embodying my invention, and illustrates an adaptation of my invention in the 10 construction of a tester tool for connecting to a casing in determining the level of cement by the vibration method referred to above. This view shows the tool gripping the casing, a portion of which is illustrated in cross-section.

15 Fig. 10 is a view similar to Fig. 9, but showing the tool released and ready to be withdrawn.

Fig. 11 is a cross-section on the line 11—11 of Fig. 10 upon an enlarged scale.

20 Fig. 12 is a section on the line 12—12 of Fig. 9, showing the slips set.

Fig. 13 is a section at the same point as Fig. 12, but after the rotation of the mandrel has gripped the slips on the casing.

25 Fig. 14 is a view of the tester assembled on the end of the drill stem.

Before proceeding to a more detailed description of the invention, it should be stated that in the present specification, I have described my improvements as applied to a tool of the spear type, and a tool of the socket type. In both of these types I prefer to provide a slip carrier or cage which carries the slips, so that they have a limited radially guided movement. But the use of a cage is not essential, and in a type of spear to test for cement levels, I have illustrated a construction not using a cage for the slips. In the fishing tool of either type, the construction includes an elongated actuating member. The slips and the actuating member 30 have engaging inclined seat faces approximately conical in form, cooperating in such a way that if a relative downward movement of the slips occur with respect to the actuating member, the slips will set themselves against the face 35 of the "fish". Although the inclined seat faces of the actuating member extend circumferentially around the axis of the tool, they do not maintain a constant distance from the axis of the tool; and in the preferred form the cross-section of the actuating member at each seat face will present a plurality of slightly projecting "peaks" or "high" points that function like 40 cam faces. Between these high points the seat face recedes, or is relieved in a radial direction 45 so that the effect of dips is attained located between the peaks or high points. In the preferred construction I provide three "rises" or "high" points located 120° apart, with the dips or "low" points of the cross-section located mid-way between the high points or peaks of the 50 cams.

55 After the slips have been set against the "fish" by a slight relative upward movement or upward strain sufficient to set them, the tool string 60 is rotated in the direction in which the "fish" should unscrew; for example, toward the left, and this rotation, by reason of the cam faces, grips the slips against the "fish".

If, in the operation of the tool, it becomes 65 necessary to release the slips, this can be accomplished by subjecting the tool string to a slight downward movement sufficient to substantially relieve the string of up strain, and at the same time rotating it in the same direction that tightened the slips; and this relative rotation of the 70

actuating member and the slips is utilized to move the slips to their completely released position.

The construction of the cement level testing tool is very similar to the spear, but inverted so 5 that the "cone" necks of the mandrel have their large ends up instead of down. This gives the slips an inclined downward thrust against the casing that is favorable for imparting vibrations to the casing through the tool string. 10

Referring more particularly to the parts, and especially to the "spear" type of tool illustrated in Figs. 1 to 5, 1 indicates the lower end of the tool string to which the actuating member in the form of a mandrel 2 is secured at the lower 15 end of the tool string by a suitable tool joint 3. The mandrel 2 is preferably of the stepped wedge or "cone" type so that it presents a plurality of inclined substantially conical seat faces 4 to cooperate with corresponding slips 5, said slips 20 being of stepped wedge-form with the small ends of the "wedges" disposed downwardly.

The cross-section of the mandrel at the seat faces is geometrically speaking a triangle, the sides of which are curved lines and the angles of 25 which (formed by the intersection of the curved sides) are very obtuse, that form the "peaks" referred to above. In this way it will be seen that each slip 5 presents a plurality of inclined substantially conical seat faces 6 to engage the 30 corresponding seat faces 4 of the actuating member, or mandrel 2. The slips are preferably three in number, disposed 120° apart circumferentially around the axis of the tool, and these slips are preferably carried on a slip carrier, or in a cage 35 7 of tubular form, and having radial slots 8 (see Figs. 3 and 4), that guide the slips in their radial movements. The upper end of the cage 7 is provided with a cap in the form of a collar 9 that is attached to the cage 7 by a screw 40 thread 10. The upper end of this cage cap may limit the upward movement of the cage by striking against a shoulder 11 at the under side of the tool joint 3.

Referring particularly to Fig. 5, which illustrates the slips in their released position, it should be stated that I form the mandrel with a cross-section so that three high spots or "peaks" 12 are formed located 120° apart with relieved faces or dips 13 located between the same. The faces of 50 the dips preferably merge into the faces of the peaks (see Figs. 3-5). In the released position of the slips shown in Fig. 5, these high points, or peaks 12 of the cams, are located somewhere near the adjacent side edges of the slips. In operation the slips should be set against the face of the "fish" 14 as illustrated in Fig. 1, by giving a slight up strain to the tool string 1, and it will be evident that a rotation of the tool string 1 will cause the cam peaks 12 to move around toward the center lines of the slips, and this will force the slips outwardly and grip their wickers 15, or other engaging means, against the face of the "fish." The faces 4 of the mandrel and the corresponding faces 4a are struck on a gradually 60 changing radius that is slightly greater than one-half the outer "diameter" of the "cone" at any point in its length. And these faces lie against each other in the accurately collapsed condition 65 of the tool.

The tool string should, to grip, be rotated in the same direction that would unscrew the "fish;" and in this connection it will be evident that the greater the torque required to unscrew the "fish," the greater the force will be with which the cam 7

faces or peaks 12 force the slips against the face of the "fish."

If, or when, it becomes necessary to release the slips from the "fish" this is accomplished by effecting a relative rotation between the mandrel and the slip carrier, or cage 7, while the tool is not under an up strain. Any suitable means may be employed for this purpose, but I prefer to employ the means illustrated in Figs. 1 and 2, which 10 has been used heretofore for releasing the slips in tools of this general type. In order to accomplish this, I provide the lower end of the cage with an inclined or helical cam face 16, and at the lower end of the mandrel I provide a similar 15 inclined or cam face 17 to engage and cooperate with the face 16. In Fig. 1, the relation of these faces is illustrated at a time when the slips are set against the "fish" preparatory to gripping the same. At this time these cam faces 16 and 20 17 will have been slightly separated by the up pull that sets the slips.

The cam face 17 is preferably formed on a collar 18 carried by the lower end of the mandrel, and having an angular opening 19 within it that 25 fits over an angular shank 20 on the mandrel at this point. This angular shank and angular opening 19 effectively mount the collar 18 so that it is non-rotatable with respect to the mandrel, and so that when the mandrel is 30 rotated, these cam faces 16 and 17 will cause the cage to rise to a relatively elevated position on the mandrel, thereby sliding the slips 5 up on the stepped seat faces 4. This causes the slips to release themselves by reason of the frictional contact of the usual long friction springs 35 21 that are secured to the cage at the three intermediate points between the adjacent edges of the slips, and engaging with the casing.

The lower end of the spear may be formed by 40 a bowl 22 secured to it by a thread 23, and a set screw 24 that engages into a groove 25 to prevent any possibility of the bowl becoming unscrewed. This bowl, of course, retains the collar 18 on the mandrel, and the collar 18 in turn retains the 45 cage 7.

In order to limit the rotary movement of the mandrel with respect to the cage 7, I provide the lower end of the cage with a circumferential groove 25 on its inner face. This groove, however, does not extend completely around the 50 circumference, so that a stop 26 is left to cooperate with the projecting key 27 carried by the mandrel.

Referring to Figs. 7 and 8, which illustrate the 55 socket type tool, this tool comprises a socket 28 of tubular or shell-form, the upper end of which is supported by a sub 29 with threads 29a to enable the same to make a tool joint connection to the tool string. The inner face of this socket 60 is formed with a plurality of stepped inclined seat faces that cooperate with three slips 30, said slips being of wedge-form with the small ends of the wedges downward, and each slip presenting inclined seat faces 31 to engage with and cooperate 65 with the inclined seat faces 28a of the socket.

As illustrated in Fig. 8, the cross-section of the 70 socket does not present a uniform thickness, but it presents three cam faces 32 where the thickness of the wall has its maximum. In other words, the curve-sided triangle formed by the cams 32 has peaks that approach toward the axis of the tool, and relief faces or dips 33 located between the cams or peaks. In principle the tool 75 operates in the same way as the spear, already described; that is to say, by subjecting the tool

string to a slight up strain, the wickers 34 of the slips can be set against the face of the "fish" 35 (see Fig. 7). This, of course, is done while the dips 33 are located adjacent the central axes of the slips, and hence after the slips have been 5 set, a slight rotation of the socket will cause cam faces 32 to shove the slips inwardly in their guide slots 36, and grips them firmly against the "fish." The direction of rotation to grip the slips would, of course, be the direction which will unscrew 10 the "fish" and back it off.

In order to enable the slips 30 to be released when desired, a helical cam face 37 is provided at the lower end of the slip carrier or cage 38, and this cam face 37 cooperates with a similar 15 cam face 39 that is formed on a shoulder 40 that projects inwardly at the lower end of the socket.

After forming the helical engaging faces 37 and 39, notches 42 are cut in them so as to produce stop shoulders 43 that will engage with each other at the limit of the rotary lifting movement for the cage and slips. These shoulders 43 prevent any possibility of using too great a rotation to "kick" the slips up, and make it unnecessary to use a stop such as stop 26 in Fig. 6. 25

A stop should be provided on the cage or on the slips to prevent "mouse-trapping" the tool over a collar on the casing. For this purpose the slips 30 are preferably provided with flanges 44 that project inwardly at their upper ends to 30 engage the upper end of the fish (see Fig. 7).

The lower end of the socket may be provided with a shoe 45 attached to it by a screw thread 46. This shoe may have the usual helical or inclined guide face 47 that assists in guiding the 35 shoe over the upper end of the "fish."

The tools can be constructed so as to operate very accurately on a predetermined slight up strain, to grip the slips; and so that with any less up strain, the slips will immediately release 40 when the rotation occurs that is intended to "kick" up the slips at the helical cams to release them.

A tester tool 48 embodying this invention is illustrated in Fig. 14. This tool has a head 49 secured to the drill string 50, said head being rigid with an actuating part in the form of a mandrel including a round stem or shank 51 terminating below in a series of steps or "cones" 52 with their large ends uppermost. The lower 50 end of the head 49 has a helical cam face 53 to cooperate with a similar cam face 54 on the upper end of a loose sleeve 55, said sleeve having friction springs 56 for engaging the casing 57, and the lower end of this sleeve supports the upper ends of the slips 58 on loose pin and slot connections 59. On similar pin and slot connections 60 the lower ends of the slips support a collar 61 guided on a neck 62 of reduced diameter below the "cones" and which carries the 60 bowl 63.

The slips are tapered to correspond with the taper of the cones, and these parts are formed and correlated on their cooperating seat faces in the way set forth in describing the spear disclosed in Figs. 1 and 2. A key 64, and cooperating stop 65 on the sleeve 55, limit the relative rotation of the sleeve and mandrel. This testing tool is run down the casing with the cam faces 53 and 54 ridden up on each other somewhat as shown in Fig. 10. This holds the slips 70 58 down on the cones (see Fig. 10) and prevents the slips from being set against the casing 57. After the tool is at the level where it is to grip the casing, the tool string is then rotated 75

toward a relation such as that shown in Fig. 9. After this, a down movement of the tool string 50 will enable the "cones" 52 to force the slips 58 outwardly and cause their wickers 66 to grip the casing 57. These wickers or teeth 66 preferably incline downwardly as shown. A slight rotation of the tool string 50 in a right-hand direction would cause the slips to grip the casing with great force by reason of the fact that the peaks 67 of the cam faces 68, move into contact with the inner faces of the slips (see Fig. 13). The slips can be released from the casing by a slight upper pull to take the weight off the slips, accompanied by a left-hand rotation of the tool string 50 to bring the parts into substantially the relation shown in Fig. 10. When the helical cams 53 and 54 have this relation, the slips 58 will be held down on the "cones" 52, which keeps them in a collapsed condition enabling the tool to be withdrawn.

In Fig. 14 this tool is indicated gripped in the casing 57 at an elevated point above the cement 69. In using this tool to test a well to determine the level of the cement 69, the tool would be gripped in the casing at a succession of points extending progressively down through the well, and during each gripping operation the tool string 50 would be vibrated and the consequent vibrations of the casing in the well head would be observed. When the tool 48 is gripped at the cement 69, the vibrations imparted to the casing would be very considerably damped, which would give an indication of the cement level.

The mode of operation of the improvement will now be described.

In the spear illustrated in Figs. 1 and 2, it should be understood that the spear would be lowered into the casing 14 while in the collapsed condition illustrated in Fig. 2, and with the helical cam 16 in the relation indicated in Fig. 2. When the tool has been lowered to the desired level in contact with the fish or casing 14, the tool string 1 would be rotated in a left-hand direction, which would permit the cage or slip carrier 9 to move relatively downwardly on the mandrel, and permit the wickers 15 to touch the casing 14. Then a slight upward pull on the tool string would set the slips firmly against the casing, after which a further rotation of the tool string in a left-hand direction would bring the peaks of the cam-form cones more nearly under the medial axes of the slips as indicated in Fig. 3, which would force the same outwardly against the casing 14, and a continued rotation in a left-hand direction will cause the tool to unscrew the fish. If it should be necessary at any time to release the tool from the fish within the well, or when releasing the tool from the fish after pulling the same from the well, this would be accomplished by reducing the up strain on the tool string so that there is substantially no upward pull on the slips, whereupon a slight rotation of the tool string in a right-hand direction through the agency of the helical surface 16 will push the slips up on the mandrel and release them.

In the socket type of tool illustrated in Figs. 7 and 8, substantially the same procedure is had, it being understood that the slips 30 are in an elevated position when the socket is run down the well. After having positioned the tool over the upwardly projecting end of the fish 35 an upstrain on the tool string will set the slips 30 against the fish, whereupon a rotation of the tool string in a left-hand direction will cause the

cam faces on the inner side of the shell of the socket to force the slips 30 inwardly and grip the fish. The tool can be released by relieving the up strain and rotating the tool string further in a left-hand direction, which will cause the helical faces 37 and 39 to engage and push the slips up to an elevated position and disengage them from the fish.

In operating the testing tool shown in Figs. 9 and 10, the tool is run down the well with the helical cams 53 and 54 in the relation shown in Fig. 10. This holds the slips collapsed, and after the tool has arrived at the level where it is to grip the casing, a right-hand rotation of the tool will bring the cam surfaces 53 and 54 more or less into the relation shown in Fig. 9, which will permit the mandrel to move down relatively to the slips. Such a down movement would set the slips against the casing, after which a slight rotation of the tool string 50 with weight on it, will cause the cam faces of the "cones" 52 to move the slips out to grip them on the casing. The release of the slips will be accomplished by a rotation in the same direction with substantially no down pressure on the slips. This, through the agency of the helical faces 53 and 54, will move the slips down into the relation shown in Fig. 10, collapsing the tool, and permitting it to be withdrawn.

It is understood that the embodiment of the invention described herein is only one of the many embodiments this invention may take, and I do not wish to be limited in the practice of the invention, nor in the claims, to the particular embodiment set forth.

What I claim is:

1. In a fishing tool, the combination of a slip-carrier, a plurality of slips carried thereby, said slips having wedge-form portions of reduced thickness toward their lower ends, with longitudinally inclined seat-faces on one face, and means on their opposite faces for gripping the "fish," an elongated actuating member to be attached to a tool-string, having a plurality of longitudinally inclined annular seat faces for engaging the seat faces of the slips, and operating by an upward pull to set the slips against the "fish," said annular seat faces having circumferentially spaced cam faces with dips between peaks of the cam faces, the faces of said dips and peaks merging into each other, and operating when the actuating member is rotated in one direction after setting the slips, to grip the slips on the "fish," said slip carrier having a cam face adjacent its lower end, and a collar carried by the lower end of the actuating member having a cam face to cooperate with the last-named cam face, said last-named cam faces being disposed substantially helically around the axis of the tool and inclined in a direction enabling the same to cooperate when the actuating member is rotated in the same direction as before with substantially no up strain, to raise the slip-carrier relative to the actuating member and thereby release the slips from the "fish."

2. In a deep well tool for gripping tubing in the well, the combination of a plurality of slips, said slips having wedge-form portions of reduced thickness toward one end with longitudinally inclined seat faces on one face and faces on their opposite sides for gripping the tubing, an elongated actuating member to be attached to a tool string, having a plurality of longitudinally inclined circumferential seat faces for engaging the seat faces of the slips and operating by

movement in one direction to set the slips against the tubing, said circumferential seat faces having circumferentially spaced cam faces with dips and peaks therein, the faces of said dips and said peaks merging into each other and operating when the actuating member is rotated in one direction after setting the slips, to grip the slips on the tubing, a collar associated with the slips having a substantially helical cam face and a collar carried by the actuating member having a substantially helical cam face, said helical cam faces inclined so that they will cooperate when the actuating member is rotated in the same direction as before with substantially no pressure exerted on the slips, to cause a relative longitudinal movement between the slips and the actuating member, and thereby release the slips from the tubing.

3. In a deep well tool for gripping tubing in the well, the combination of a plurality of slips, said slips having wedge-form portions of reduced thickness toward one end with longitudinally inclined seat faces on one face and faces on their opposite sides for gripping the tubing, an elongated actuating member to be attached to a tool string, having a longitudinally tapered cross-section presenting a plurality of curved cam faces with peaks and dips on each side of each peak merging into the same for engaging the seat faces of the slips and operating by a rotation of the tool in one direction while the tool is subjected to a longitudinal strain to set the slips against the tubing and cause the same to forcibly grip the tubing; and means moving with the actuating member and brought into action by rotation of the actuating member in the same direction as before when there is substantially no longitudinal strain on the tool, for effecting the sliding of the slips longitudinally relative to the actuating member, and thereby effecting the release of the slips from the tubing.

4. In a fishing tool for backing off tubing connected by threaded joints, the combination of a slip carrier, a plurality of slips carried thereby, said slips having wedge-form portions of reduced thickness toward their lower ends with longitudinally inclined seat faces on one face and means on their opposite faces for gripping the tubing, an elongated actuating member to be attached to a tool string, said actuating member having a cross-section presenting curved cam-

form side faces the middle portions of which constitute dips of the cams, said side faces intersecting each other to form cam peaks, and forming seat faces for the slips inclined longitudinally of the actuating member, said actuating member operating by a movement in one direction to set the slips against the tubing, and operating when the actuating member is rotated after setting the slips, to grip the slips on the tubing; and correlated engaging means on the actuating member and on the slip carrier brought into engagement with each other by the rotation of the actuating member in the same direction as before when there is substantially no strain, to raise the slip carrier relative to the actuating member, and thereby release the slips from the tubing.

5. In a fishing tool of the socket type, the combination of a cage for carrying slips, a plurality of slips carried thereby, said slips having wedge-form portions of reduced thickness toward their lower ends with longitudinally inclined seat faces on their outer sides, and means on their inner faces for gripping the "fish," a sleeve-form socket to be attached to a tool string, having a plurality of longitudinally inclined annular seat faces for engaging the seat faces of the slips, and operating by an upward pull to set the slips against the outer side of the fish, said socket having a cross-section at its inner wall presenting cam-form side faces intersecting each other to form cam peaks approaching the longitudinal axis of the socket, said curved faces forming seat faces inclined longitudinally of the socket to enable the said upward pull to set the slips against the outer side of the fish, and operating when the socket is rotated after setting the slips, to grip the slips on the fish, and correlated engaging means on the socket and on the cage having engaging faces inclined so that when the socket is rotated in the same direction as before with substantially no up-strain, said correlating engaging means will raise the cage relative to the socket and thereby release the slip from the fish.

6. A fishing tool for actuating slips to back off tubing connected by threaded joints, having an actuator for the slips with a cross-section presenting a plurality of circumferentially disposed curved cam faces with peaks, and dips on each side of each peak merging into the same.

IDRIS THOMAS.
